SHELF

Robert J. Slavsky, Detroit, Mich., assignor to
Shaw and Slavsky, Inc., Detroit, Mich., a corporation of Michigan

Application December 7, 1953, Serial No. 27,968

Term of patent 14 years

(Cl. D33—3)

To all whom it may concern:

Be it known that I, Robert J. Slavsky, a citizen of the United States, residing at Detroit, in the county of Wayne and State of Michigan, have invented a new, original, and ornamental Design for a Shelf, of which the following is a specification, reference being had to the accompanying drawing, forming part thereof.

I claim:

The ornamental design for a shelf, as shown and described.
